UNITED STATES PATENT OFFICE.

CHARLES T. LIBBY AND GEORGE G. BABCOCK, OF PORTLAND, MAINE; SAID BABCOCK
ASSIGNOR TO SAID LIBBY.

LINOTYPE-MACHINE.

No. 873,251.

Specification of Letters Patent.

Patented Dec. 10, 1907.

Application filed December 26, 1905. Serial No. 293,172.

To all whom it may concern:

Be it known that we, CHARLES T. LIBBY and GEORGE G. BABCOCK, both citizens of the United States, and residents of Portland, 5 in the county of Cumberland and State of Maine, have invented new and useful Improvements in Linotype-Machines, of which the following is a specification.

This invention relates to improvements in 10 linotype machines of the general character of the so-called Mergenthaler linotype machine described in United States Letters Patent Number 436,532, dated September 16, 1890.

15 It relates to means for raising the assembling elevator repeatedly in consonance with the other parts of the machine, the machine running constantly instead of stopping at the end of each revolution.

20 It also relates more particularly to means for raising the assembling elevator automatically upon the operator touching a key instead of manually.

25 It also relates to means for raising the elevator automatically either upon the operator touching a key or when the machine comes to its proper position provided a key has been already touched.

It also relates to specific mechanism adapted 30 to bring about the above results.

It also relates to certain details of construction hereinafter fully explained.

It is tributary to applicant, Charles T. Libby's pending application Serial Number 35 197,782, allowed November 11, 1905.

In the drawings herewith accompanying and making a part of this application, Figure 1 is a perspective detail view of our improved mechanism and so much of said 40 Mergenthaler linotype machine as is necessary to illustrate the construction and operation of our invention; Fig. 2 is an elevation of the piston-carrying lever and its attachments; Fig. 3 is a plan view of the same; Fig. 4 is a detail elevation of a part of Fig. 1 taken from the opposite side; Fig. 5 is a detail plan view partly in section showing both the slotted and the make-and-break connection between the elevator raising rod and the elevator 45 raising bell crank lever; Fig. 6 is a detail sectional view showing part of said bell crank lever and adjustable anti-friction roll; Fig. 7 is a detail elevation showing the elevator locking latch and mechanism for operating it, some parts being removed; Fig. 8 is 55 a perspective view of the cam-face lever; Fig. 9 is a detail perspective view of the counterbalance spring hook; Fig. 10 is a detail edge view of a part of the elevator lever link and latch hold and Fig. 11 is a detail view of 60 the speed key brake rod.

Same letters of reference refer to like parts.

In the drawings herewith accompanying and above referred to we illustrate one form of our improvement which is especially well 65 adapted to accomplish the result aimed at.

Referring to said drawings A represents the base, B parts of the main frame, C the line delivery carriage, D the line delivery carriage lever, E the line delivery carriage 70 shaft, F the assembling elevator, G a pivoted latch for retaining the line delivery carriage, H the line delivery carriage releasing pin, I the needle on the assembling elevator for operating said pin, J the hook for supporting the assembling elevator, K the assembling elevator releasing bar, M the assembling elevator lever, N the assembling elevator lever link, O the assembling elevator counter balance spring and P one of the main 75 cams on the main cam shaft. These parts may be substantially the same and operate in substantially the same manner as in said Mergenthaler machine, namely, when the assembling elevator loaded with matrices arrives 80 up, the hook J engages and almost simultaneously the needle I pushes up the releasing pin H and knocks off the latch G whereupon the line delivery carriage goes to the left and starts a revolution of the main cam driving 85 shaft, not shown. Hook J holds the elevator up until the line of matrices has passed out, whereupon it is knocked off by the releasing bar K and the elevator drops down. The reciprocation of the line delivery carriage is effected by a rocking of its shaft about forty-five degrees and on its return it is again latched and held by latch G. Meanwhile the main cam driving shaft continues its movement and at the end of a single revolution 90 95 automatically stops, unless the assembling elevator has been again sent up. The main cam driving shaft only goes round once for each time the assembling elevator is put up. The assembling elevator cannot be put up 100 until the line delivery carriage has returned to its first position, otherwise the line of matrices would be in the path of the returning 105

line delivery carriage. The line delivery carriage shaft is motionless at the time the assembling elevator goes up.

In the application of our improvements to 5 said Mergenthaler machine a bracket 1 is mounted on the frame of the machine. On bracket 1 is pivotally mounted a bell crank lever S having a backwardly extending arm 2 and a vertically extending arm 3. The main 10 elevator spring 4 having one end attached to the base and the other through an intermediate adjusting link 5 to arm 2 tends constantly to draw arm 2 downwardly, the downward movement of arm 2 being limited by an adjusting screw 6 adjustably set in a lug 7 on bracket 1 as seen in Fig. 4. The vertical arm 15 3 carries an anti-friction roll 8 and is operated by a cam face 85 on lever 9 set on the line delivery carriage shaft. The spring 4 and cam face lever 9 operate to move the bell 20 crank lever in opposite directions.

On the shaft of the assembling elevator lever is a bell crank lever T one arm 10 extending under the assembling elevator lever for 25 the purpose of raising the elevator and the other arm 11 extending downwardly. A connecting rod 12 extending backwardly inside the machine is pivotally secured, one end to arm 11 of lever T and the other end to arm 30 3 of lever S by means of a stud 13 working in an elongated slot 14 in said lever, the length of the slot being sufficient to permit the assembling elevator to pass through the full length of its movements without said stud 35 binding at either end of the slot. Besides the slotted connection between rod 12 and arm 3 there is also a make and break connection consisting of a latch 15 pivotally mounted on said rod, its free end extending beyond 40 the end of the rod and adapted to engage a latch hold 16 on arm 3. The free end of the latch extends beyond said latch hold in the path of said cam face lever, whereby said latch may be disengaged by said lever, said 45 lever being positioned on the line delivery carriage shaft so that it will disengage said latch at the moment when the line of matrices has passed out of the assembling elevator.

50 Secured to the front end of bracket 2 is a vertical bracket 17 on which is pivotally mounted a latch 18 in such position as to engage a latch hold 19 on the assembling elevator lever link, when the assembling elevator is down. A spring 20 tends constantly to force latch 18 forward, the forward movement being limited, when not in engagement with its latch hold, by a stop pin 21 set in the bracket. Latch 18 is disengaged automatically as follows. On the surface of one of the main cams on the main cam shaft of the machine, of which only one (marked P) is shown, is placed a small bevel faced projection 22. Mounted in a bracket 23 secured to the frame

is a reciprocating rod 24 having on one end an 65 anti-friction roll 25 positioned in the path of projection 22 in such way that rod 24 receives an endwise thrust as projection 22 passes it as the cam rotates. On a bracket 70 26 secured to bracket 1 near its rear end is mounted a simple lever U, its upper arm 27 positioned in the path of rod 24. To the lower arm 28 is pivotally attached a long link 29 reaching through the machine, its other end being pivotally attached to the lower arm 30 of a piston lever V pivotally secured to the bracket 1. The upper arm 31 of this lever is equipped with a piston 32 set in a chamber 33 within which behind said piston is a spiral spring 34. On bracket 17 below 75 35 latch 18 is pivotally mounted a latch lever 39 so constructed and positioned that its lower arm is in the path of piston 32 while its upper arm engages latch 18.

The mechanism thus far described is all 85 that is employed in the first of the three ways in which the device works, namely, to raise the elevator automatically and repeatedly in consonance with the other movements of the machine, the main cam revolving continuously without stopping, whereas in the standard linotype machine this cam stops at the end of each revolution unless another line of matrices is first sent up. In this mode of operation, a line of matrices having 90 been sent up and the main cam shaft started on a revolution, when the beveled projection 22 comes in contact with the anti-friction roll it gives rod 24 an endwise thrust which in turn through intermediate mechanism 95 forces arm 31 of the piston lever forward until the piston strikes latch lever 39 unlatching latch 18 whereupon the main elevator spring 4 pulling lever S and lever S pulling on rod 12 raises the elevator which in turn releases the line delivery carriage. The movement of the line delivery carriage shaft, which is a rocking movement through an angle of about forty-five degrees, effects two results. First, the end 84 of the cam face 100 lever engages the end of latch 15 and forces it up unlatching it at the moment when the line of matrices has passed out of the assembling elevator. Whereupon the assembling 105 elevator, hook J having simultaneously been 110 unhooked as in the existing machine, drops down by gravity and relatches and the cam face 85 of lever 9 engages anti-friction roll 8 on lever S, forcing the latch-hold 16 forward under the latch 15 until they reengage, and 115 at the same time by turning the lever 3 on its pivot reenergizing or extending spring 4 which is attached to one end of said lever and at its other end to the framing.

120 At the end of the movement of the line delivery carriage shaft, another line of matrices having just been sent up, the main cam P is 125 continued in motion as in said Mergenthaler

machine and again at the same point in its revolution through intermediate mechanism releases the assembling elevator as before.

To adapt the machine to the second 5 method of operation wherein the assembling elevator is raised automatically upon the operator touching a key, a key 40 is pivotally mounted on arm 41 of the latch bracket in such position that the back end of the key 10 can be moved into or out of the path of the lower end of latch lever. The back end of key 40 is held down yieldingly by a spring 42 interposed between the key and a lug 43 on bracket arm 41.

15 Secured to the back end of the piston is a projecting pin 35 traveling in a slot 36 in arm 31, one end of said pin extending beyond the slot under the bottom edge of a latch 37 mounted on arm 31. Said latch besides its 20 latching face has an additional sloping face 38 against which said pin strikes and raises and holds up the latch as the piston moves forward. A rearward arm 83 of bracket 17 carries a latchhold 82 for this latch.

25 When operating by the second method when the piston lever is forced forward, as before described, the advance of the piston and lower end of the latch lever being blocked by the end of the key, the piston 30 will be forced back into its socket compressing the spring behind it; the piston pin at the same time passes out from under the portion 38 of the latch, the latch thereupon engaging its latch hold 82 on arm 83 of bracket 17.

35 When the operator is ready to send up the elevator, he depresses the key, the back end clearing the latch lever, whereupon the piston, spring-impelled, impinges the lower end of the latch lever with sufficient force to 40 cause the upper end to impinge the elevator latch and disengage it from its hold. At the same time the piston pin engaging the beveled edge of the piston latch disengages it from its hold allowing the piston lever to 45 drop back, again forcing anti-friction roll 25 on the end of the thrust rod back into the path of the beveled projection on cam P. Meanwhile, when the elevator went up, the elevator latch under the action of its spring 50 20 moved forward until it engaged its stop pin 21 forcing the latch lever back so that the back end of the key again dropped into the path of the latch lever, so that the piston will be again compressed by the ensuing 55 revolution of cam P as aforesaid.

To adapt the machine to the third method of operation wherein the elevator is raised automatically either upon the operator touching a key as 40 or when the machine 60 comes to its proper position provided key 40 has been already touched, the elevator latch hold, is so placed on the elevator lever link that, when the elevator latch is in engagement with its hold the latch is out of engagement with its stop pin. In consequence of

this construction when the elevator drops and relatches, the latch 18 is held a slight distance away from the end of the latch-lever 39, as seen in Fig. 7. When in this position and the operator has a line of matrices 70 ready, if he touches key 40, releasing the lever 39 before the line delivery carriage has returned to its proper position, the latch lever 39, impelled by its spring 58, rocks on its pivot and its lower end moves under the end 75 of key 40, which has been raised, and prevents said key from dropping into locking engagement with said lever. In this situation, when the cam P arrives at a point where it operates to force the piston 32 80 against the lower end of the latch lever, finding no resistance from key 40, it unlatches latch 18 sending up the elevator without anything further done by the operator. This permits the operator to touch key 40 at any 85 time regardless of the progress of the parts of the machine during its cycle of movement, the beveled projection 22 on cam P being so placed that the elevator holding latch is disengaged at the earliest moment 90 that the elevator can safely go up and promptly return without care on the part of the operator and without loss of time.

The devices for changing the machine from one method of operation to another are 95 as follows. Pivotally mounted on bracket 41 above the front end of key 40 is a so called speed key 44, the top end thereof finished as a button adapted on the front side to be pressed back by hand and on the back side 100 to receive the impingement of the spur of the speed key brake described to return it. A notch in the back edge spans a stop pin 56, the edges of the notch limiting the backward and forward movements of the speed key. 105 The operative part is a projection 46 at the bottom end which touches nothing when the button is front but as the button is pressed back engages a cam surface 45 on the top edge of key 40, forcing it down and holding 110 it out of action. The speed key brake 47 may be mounted on the same pivot 81 as key 40. On the top end is constructed a spur adapted to impinge the back side of the button of the speed key, and the bottom end 115 carries the speed key brake rod 49 to force the elevator latch lever back from under the back end of key 40. On its front edge is constructed a button to be pressed down by hand and at the bottom end is a face with a 120 socket for holding one end of a spiral spring 55, the other end held in a socket in the edge of bracket 41, to return it. With the speed key back and the back end of the key thereby held up, there is nothing to block the 125 automatic sending up of the elevator every time the piston comes forward. This full speed method is desirable as long as the operator is able to compose his lines of matrices fast enough. The operator may shift to the 130

start-and-stop method when unable to keep up with the full speed of the machine by pressing down on the speed key brake button, thereby bringing the speed key front to 5 release the front end of the key and forcing the elevator latch brake back so as to permit the back end of the key to drop into its blocking position, as above described.

Having now described the main parts of 10 our improvements we will proceed to describe some minor details of construction.

A lug 51 besides serving as a stop to limit the downward movement of key 40 serves also as a rest for the back end of the speed 15 key brake rod 49. The speed key brake rod as shown has a hooked end 52 inserted in a perpendicular slot 53 in the brake, the hooked end being so shaped that when turned horizontally it cannot tumble out of 20 the slot. The movement of the speed key brake is limited by the projecting pivot 87 of the speed key which projects into a slot 54 in the brake. The cam face on the top edge of the key is so constructed that its 25 highest point 45 is reached by the contact point 46 of the speed key before the speed key is pushed clear back and said face is then made to recede slightly so that the back end of the key falls slightly before the speed key 30 is way back. This construction serves to prevent the speed key falling front from the jar of the machine.

The elevator latch is held yieldingly by 35 spring 20 and the elevator latch lever is held yieldingly by spring 58, the latch spring being the stronger in order that when the elevator goes up it will be effective to force the latch forward against its stop pin thereby forcing the latch lever back against the 40 resistance of the latch lever spring, the latter however having sufficient strength to force the latch lever front under the end of the key before the forward movement of the piston. It is manifest that the piston spring must be 45 stronger than the latch spring as otherwise instead of unlatching the latch the piston would be forced back upon its own spring. The elevator rod latch is held yieldingly by a spring 59. The piston latch is held yieldingly by a spring 60. In order to prevent 50 the elevator latch, when it is unlatched by the contact of the end of the cam face lever, relatching before the elevator gets down, the cam has a sloping face 61 down which the 55 end of the latch drags sustaining the end of the latch away from its latch hold until the last moment when this face terminates vertically as seen at 86 and permits the latch to drop into engagement with its latch hold. 60 As a safety precaution in event the elevator should fail to come down leaving latch 15 in the path of the returning cam lever 9, the rear edge 62 is beveled so as to thrust the latch to one side instead of breaking it; and 65 to permit this movement of the latch, the

latch at its rear end is beveled as seen at 63 and behind the beveled end a spiral spring 64 holds the latch yieldingly against said movement. To further facilitate this movement the bearing face of the pivot is made 70 somewhat longer than the thickness of the latch and the hole 65 in the latch through which the pivot pin 66 passes is slightly beveled as shown in dotted lines, Fig. 5.

To contribute to the light running of the 75 device the usual counterbalance spring O of the standard machine may be used and for convenience it is attached at its back end to hook 67 on the latch bracket and its front end hooked into the bell crank lever T above 80 the elevator rod as shown in Fig. 1.

To prevent the thrust rod 24 turning round thereby shifting its anti-friction roll from the path of the beveled projection 22, and to limit its endwise movement a pin 87 85 set in the rod supporting bracket projects through a slot 88 in the rod. The length of the thrust rod is made adjustable by a set screw 70 in its front end. To adjust the main spring 4 a turnbuckle 71 is interposed 90 between it and the bell crank. To adjust the backward movement of the piston lever, an adjusting screw 72 set in a lug thereon is so positioned as to strike the key board frame, not shown. The anti-friction roll on bell crank S is adjusted by being mounted on an eccentric pin 73 held in any given position by a set screw 74. The cam face lever is made adjustable endwise and sidewise on the line delivery carriage shaft by means of a 100 clamp 75 and screws 76 passing through the clamp into the lever. The latch hold on the elevator lever link is made adjustable by means of screws 77 passing through elongated holes 78 shown in dotted lines in Fig. 105 10. The adjusting screw 6 limits the downward movement of bell crank S at the moment when it has been unlatched and the cam face lever has not yet engaged the anti-friction roll. The piston lever has a constant tendency to fall back, which may be imparted to it in any convenient way as by mounting it so that its center of gravity is 110 outside of its pivot.

Having thus described our invention and 115 its use, we claim:

1. In a linotype machine, in combination, an assembling elevator, elevator raising mechanism comprising a source of power and intermediate connecting mechanism, a make and break connection in said intermediate mechanism, a cam lever rigidly mounted on the line delivery carriage shaft having one face adapted to break the connection at pre-determined times, and a second face adapted 120 to energize the elevator raising mechanism.

2. In a linotype machine, in combination, an assembling elevator, elevator raising mechanism comprising a source of power and intermediate connecting mechanism, a make 125

- and break connection in said intermediate connecting mechanism, a cam lever rigidly mounted on the line delivery carriage shaft having one face adapted to break the connection and a second face adapted to energize the elevator raising mechanism and restore the connection in the make and break mechanism.
3. In a linotype machine, an assembling elevator, elevator raising mechanism comprising a source of power and intermediate connecting mechanism, a make and break connection in said intermediate mechanism, a pivot latch adapted to hold the elevator down and means operable by a moving part of the machine to release said elevator holding latch.
4. In a linotype machine, in combination, an assembling elevator, elevator raising mechanism comprising a source of power and intermediate mechanism, a make and break connection in said intermediate mechanism, a pivoted latch for holding the elevator down, a pivoted latch lever, one end in engagement with and adapted to disengage the latch and the other in the path of mechanism operable by some moving part of the machine to operate the latch lever, to disengage the latch.
5. In a linotype machine, in combination with a mechanically actuated assembling elevator, means for holding the elevator down, means for disengaging said holding means comprising a spring impelled piston mounted in a pivoted lever and means actuated by a moving part of the machine to operate said piston lever to automatically release the latch.
6. In a linotype machine, in combination with a mechanically actuated assembling elevator, means for holding the elevator down, a pivoted latch lever adapted to disengage said holding means, a piston operable automatically by some moving part of the machine to operate said latch lever and means for holding said latch lever temporarily out of engagement with the latch.
7. In a linotype machine, in combination with a mechanically actuated assembling elevator, means for holding the elevator down, a pivoted latch lever adapted to disengage said holding means, a piston operable automatically by some moving part of the machine to operate said latch lever, a pivoted key adapted to engage and hold said latch lever temporarily out of engagement with the latch until released by the operator and means for holding said key positively out of engagement with said latch lever.
8. In a linotype machine, in combination with the assembling elevator, a bell crank and rod movably fastened together by a slotted connection, with a latch on one and latch pin on the other, and connecting operating and controlling mechanism for automatically actuating said elevator.
9. In a linotype machine, the vertically movable assembling elevator and mechanically actuated mechanism for operating same comprising a single lever adapted to be attached to a moving part of the machine made with two faces, one adapted to knock a latch from its latch hold and the other adapted to force the latch hold back under the latch, in combination with such latch and latchhold, connecting mechanism and devices for periodically detaining and releasing said elevator.
10. In a linotype machine, the vertically movable assembling elevator and mechanically actuated mechanism for operating same comprising a latch and latchhold and a device adapted to unlatch the latch, prevent its prematurely relatching and duly relatch it, in combination with connecting mechanism and devices for periodically detaining and releasing said elevator.
11. In a linotype machine, the assembling elevator and automatic actuating mechanism therefor, in combination with a latch and automatic mechanism for operating the latch consisting of an endwise thrust rod actuated by a moving part of the machine and connecting mechanism between said thrust rod and said latch.
12. In a linotype machine, a latch with a sloping face, and a spring pushed piston carrying a pin which by engaging said sloping face automatically unhooks said latch, in combination with the assembling elevator and automatic actuating mechanism therefor, a latch for holding down said elevator and mechanism of which said first named latch, piston and pin are a part for operating the last named latch.
13. In a linotype machine, the assembling elevator and automatic actuating mechanism therefor, in combination with a two-piece latch for holding said elevator down and a manually operated key, said latch adapted in one position to be held by said key and in another position upon said key being pressed to hold said key out of action, and connecting mechanism for operating said latch.
14. In a linotype machine, a key adapted to block the unhooking of a latch and made with a cam face containing a high place adapted to force said key out of its blocking position and prevent it from jarring back into its blocking position, in combination with the assembling elevator and automatic actuating mechanism therefor, the latch to hold the elevator down, automatically actuated mechanism for operating the latch and mechanism for locking out of and letting into action the key first mentioned.
15. In a linotype machine, in combination, an assembling elevator, means for actuating said elevator, a latch for holding said elevator down, a latch lever adapted to release

- said latch, means adapted automatically and periodically to actuate the latch lever to release the latch and means for blocking the action of said latch lever.
5. 16. In a linotype machine, in combination, an assembling elevator, means for actuating said elevator, a latch for holding said elevator down, a latch lever adapted to release said latch, means for blocking the action of 10 said latch lever and yielding reciprocating mechanism adapted to engage automatically and periodically said latch lever and to operate the latch when the latch lever is unblocked and ineffective therefor by reason of 15 its yielding when the latch lever is blocked.
17. In a linotype machine, in combination, an assembling elevator, means for actuating said elevator, a latch for holding said elevator down, a latch lever adapted to release 20 said latch, means for blocking the action of the latch lever and reciprocating mechanism having a piston yieldingly mounted therein adapted to engage automatically and periodically said latch lever and to operate the 25 latch when the latch is unblocked and ineffective therefor by reason of its yielding when the latch lever is blocked.
18. In a linotype machine, in combination, an assembling elevator, a latch-hold on said 30 elevator, means for raising said elevator, a spring-pressed latch for holding said elevator down adapted to engage said hold, a stop pin in the path of said latch, a spring-pressed latch lever adapted to be operated to release 35 said latch, the positions of the stop pin and hold being such that when the latch is in engagement with its hold it is slightly out of contact with its stop pin and latch lever, means for blocking and unblocking said 40 latch lever and means for actuating said latch lever.
19. In a linotype machine, in combination with a mechanically actuated assembling elevator, a spring-pressed latch to periodically 45 hold said elevator down, a lever actuated from a moving part of the machine to throw out said latch, a key lever with one end adapted to block the automatic releasing motion of said lever automatically and the 50 other end to be pressed by the operator to withdraw it.
20. In a linotype machine, an assembling elevator, elevator actuating mechanism, a spring-pressed latch for periodically holding 55 down said elevator, automatically actuated mechanism for operating said latch, a simple lever for automatically and positively blocking the last named mechanism adapted to be withdrawn by being pressed by the operator. 60
21. In a linotype machine, an assembling elevator, elevator actuating mechanism, a spring-pressed latch for periodically holding down said elevator, automatically actuated mechanism for operating said latch, a simple lever for automatically and positively blocking the last named mechanism adapted to be withdrawn by being pressed by the operator, a device for locking the simple lever out of action. 70
22. In a linotype machine, in combination, an assembling elevator, elevator actuating mechanism, a spring-pressed latch for periodically holding down said elevator, automatically actuated mechanism for operating 75 said latch, a simple lever for automatically and positively blocking the last named mechanism adapted to be withdrawn by being pressed by the operator, devices for locking the simple lever out of action and 80 letting it into action.
23. In a linotype machine, in combination with a mechanically actuated assembling elevator, a pivoted latch for holding the elevator down, a pivoted latch lever, one end 85 in engagement with and adapted to disengage the latch and the other in the path of mechanism operable by a moving part of the machine to operate the latch lever to disengage the latch. 90
24. In a linotype machine, in combination with a mechanically actuated assembling elevator, a two-piece latch for holding said elevator down, two opposite-acting devices for operating said two-piece latch, one actuated automatically from a moving part of the machine, the other manually, so constructed that the assembling elevator, when the manual device has been worked before the automatic device has acted, remains 100 waiting until the latter acts. 95
25. In a linotype machine, a key adapted to block the unhooking of a latch, in combination with the assembling elevator and automatic actuating mechanism therefor, the latch to hold the elevator down, automatically actuated mechanism for operating the latch and mechanism for locking out of and letting into action the key first mentioned. 110
